UNITED STATES PATENT OFFICE

LEON L. WHITE, OF TAMPA, FLORIDA

BUCKLE

Application filed November 17, 1928. Serial No. 320,131.

This invention relates to buttons, buckles and clasps and more particularly to a buckle or fastener especially designed to permit a sanitary napkin to be engaged with the depending front and rear tabs of a belt but may also be employed for other purposes.

One object of the invention is to provide a buckle which may be firmly connected with the lower portion of a suspending tab and a napkin drawn snugly into place while being engaged with the buckle.

Another object of the invention is to provide a buckle having prongs for penetrating an end portion of a napkin and means for applying pressure to the end portion of the napkin in order to cause the prongs to easily penetrate it and to retain the napkin end in engagement with the prongs.

Another object of the invention is to so form the pressure plate that the free penetrating ends of the prongs may project from a main plate of the buckle a sufficient distance to readily penetrate the napkin.

Another object of the invention is to allow the end portion of the napkin to be easily drawn upwardly between the main plate and pressure plate.

Another object of the invention is to provide a buckle of this character which may be formed from a unitary blank of resilient sheet metal and thereby cheaply produced.

The invention is illustrated in the accompanying drawings, wherein:

Figure 1 is a perspective view showing a sanitary napkin suspended from a belt through the medium of the improved buckle.

Figure 2 is a perspective view of the buckle and a portion of a suspending tab to which it is secured.

Figure 3 is a longitudinal sectional view through the buckle, taken on the line 3—3 of Figure 2, with the suspending tab shown in elevation.

Figure 4 is a transverse sectional view taken on the line 4—4 of Figure 2, with the suspending tab omitted.

Figure 5 is a view of the blank from which the buckle is formed.

The improved buckle constituting the subject matter of this invention has been shown

applied to the depending front and rear tabs 1 of a sanitary belt 2 in order to support a napkin 3 but it is to be understood that the buckle may be used for other purposes for which it may be found adapted. This buckle 55 is formed from a blank, shown in Figure 5, and referring to this figure, it will be seen that the blank includes a body portion 4 forming the main plate 5 of the buckle. A side extension or wing 6 projects from one side 60 of the body portion 4 and when folded along the dotted line 7, forms a pressure plate 8 which extends transversely across the main plate 5 in spaced relation thereto. Prongs 9 are struck from the body portion and bent 65 so that their free penetrating ends project forwardly from the main plate, as shown in Figure 3, and the pressure plate is pressed outwardly within the confines of the dotted line 10 to form a pocket 11 into which the 70 free ends of the prongs 9 project under normal conditions. This formation also allows a portion of the napkin 3 to be forced into the pocket, as shown at 12 in Figure 3, and by referring to this figure it will be seen that, 75 due to this formation, the prongs will very effectively penetrate the napkin and there will be no danger of the napkin slipping out of engagement with the prongs. When the napkin is to be engaged with the buckle, an 80 end portion of the napkin is slid into place between the pressure plate and the main plate and drawn upwardly, and in order to allow the napkin to be easily slid behind the pressure plate, the lower corner portion of the 85 pressure plate is bent outwardly along the dotted line 13 to form a guide lip 14. The end of the napkin can be easily drawn upwardly past the prongs but it cannot slip downwardly as the prongs penetrate the napkin and thereby firmly grip it and hold it against downward movement. In order to remove the napkin it is necessary to slide it upwardly in a diagonal direction, thereby 90 causing it to move out of position between the main plate and the pressure plate.

In order to connect the lower end of the buckle with the suspending tab 1, there has been provided spurs 15 projecting downwardly from the lower end of the body por- 100

tion 4 and the body portion is bent upwardly along the dotted line 16 to form a flange 17 between which and the body portion the lower end of the suspending tab 1 is gripped, 5 as shown in Figure 3 of the drawings. After the lower end of the tab has been gripped by the flange 17, it is drawn downwardly in front of the flange until the prongs 15 penetrate the tab. The suspending tab extends upwardly 10 against the inner face of the main plate and arms 18, which project from opposite sides of the main plate, near its upper end, are folded rearwardly into gripping engagement with the tab. A slot 19 is formed 15 in the upper portion of the main plate, above the arms 18, through which the tab may be passed in order to more positively connect the buckle with the suspending tab and openings 20 are formed in the body portion above 20 and below the pressure plate through which threads may be passed in order to sew the tab to the buckle. It will thus be seen that the buckle may be very firmly connected with the suspending tab of the belt and there will 25 be no danger of it slipping out of proper engagement therewith.

When a sanitary belt provided with the improved buckle is in use, it is disposed about a person's waist with the tabs 1 extending 30 downwardly at the front and rear. It will be understood that additional tabs equipped with buckles may be provided, if so desired.

When the belt is in place, one end of the napkin 3 is engaged with a buckle at the rear 35 by sliding an end portion of the napkin upwardly between the pressure plate and the main plate of the buckle until it extends slightly above the upper end of the pressure plate and a slight downward pull then exerted to cause the prongs to be firmly embedded in the napkin. The napkin is then drawn forwardly into its proper position and the forward end carried upwardly and slid into place between the pressure plate 40 and the main plate of the buckle carried by the tab at the front of the belt. Since the forward end of the napkin may be drawn upwardly as far as desired, the napkin may be drawn snugly into place without binding and 45 since this end will also be penetrated by the prongs, the napkin will be firmly held in place and prevented from accidentally slipping loose. By drawing the end of the napkin upwardly in a diagonal direction toward 50 the free side of the pressure plate, it may be easily released from the buckle when necessary. It will thus be seen that the napkin can be easily engaged with the buckle or released therefrom but when engaged with the 55 buckle there will be no danger of its end portions accidentally slipping loose.

What is claimed is:

1. A buckle comprising a main plate adapted to be secured to a suspending strip with 60 the plate disposed against the outer face of

the strip, prongs carried by the main plate and extending upwardly with their free upper ends projecting outwardly from the outer face of the plate, a pressure plate disposed in front of the main plate in covering relation to said prongs and along one side being attached to the main plate, the said pressure plate having a portion pressed outwardly to form a pocket to receive the free ends of the prongs and having a lower corner portion bent outwardly to form a lip adapted to guide a strip of material between the plates for engagement by the prongs. 70

2. A buckle consisting of a blank of sheet metal having a body portion constituting a main plate and a wing extending from one side of the body and folded to form a pressure plate extending in overlying relation to the body portion, the said body having prongs struck therefrom and the upper free ends of the prongs being bent outwardly behind the pressure plate, the said pressure plate having a portion pressed outwardly and forming a pocket receiving the free ends of said prongs, the lower end of said body being adapted to be folded upwardly to grip the lower end of a suspending tab for the buckle and terminating in spurs to bite into the tab, and arms extending transversely from the body above the side wing and adapted to be folded rearwardly into position to grip the tab. 80

In testimony whereof I affix my signature.
